poration, a corporation of Illinois

Original application March 24, 1948, Serial No.
16,809. Divided and this application February
2, 1950, Serial No. 141,951

3 Claims. (Cl. 1—49)

1

This invention relates to stapling devices or tools and particularly to stapling tools of the hammer type.

The subject matter herein claimed was first disclosed in my application filed March 24, 1948, Serial No. 16,809, now U. S. Letters Patent No. 2,501,703, granted on March 28, 1950, and of which this application is a division.

Hammer type stapling devices as heretofore manufactured have been the subject of many objections despite the convenience with which they were effective to drive staples into the work. These objections have centered in a large measure about the difficulty and cost of manufacture and the large number of parts that were needed in such manufacture. It is, therefore, an important object of this invention to simplify the manufacture of hammer type stapling devices, and an object related to the foregoing is to enable such stapling devices to be constructed in such a way as to involve but a very few parts that must be made and fitted together at relatively close tolerances.

Other and related objects are to enable such hammer type stapling devices to be so constructed as to avoid the necessity for accurate pivotal connection of the two major elements of the device; to simplify the matching of the staple driving ram with the guiding element therefor; to enable the ram and its guide to be mounted on a single element of the device; and to enable the staple driving action to be attained without marring of the surface in which the staple is driven.

In the use of stapling devices of the aforesaid character, the convenience of loading of the staples is of course an important factor, and it is therefore another important object of this invention to simplify and facilitate the staple loading operation.

Other and further objects of the present invention will be apparent from the following description and claims and are illustrated in the accompanying drawings which, by way of illustration, show a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

2

In the drawings:

Fig. 1 is a side elevational view of a stapling device embodying the invention;

Fig. 2 is a vertical sectional view taken longitudinally of Fig. 1;

Fig. 3 is a vertical sectional view showing the parts upon completion of a staple driving operation;

Fig. 4 is a horizontal sectional view taken along the line 4—4 of Fig. 2;

Fig. 5 is a front or left hand end elevational view;

Fig. 6 is an enlarged vertical section similar to Fig. 2, taken along the line 6—6 of Fig. 5 and showing an enlarged portion of the staple driving ram and the associated mechanism;

Fig. 7 is a vertical section taken along the line 7—7 of Fig. 6;

Fig. 8 is a vertical section taken along the line 8—8 of Fig. 6;

Fig. 9 is a vertical section taken along the line 9—9 of Fig. 6;

Fig. 10 is a plan section taken along the line 10—10 of Fig. 6;

Fig. 11 is a plan section taken along the line 11—11 of Fig. 6;

Fig. 12 is a plan section taken along the line 12—12 of Fig. 6;

Figs. 13, 14 and 15 are fragmental vertical sectional views showing portions of the staple loading and advancing mechanism in different positions;

Figs. 16, 17 and 18 are vertical sectional views taken respectively along the lines 16—16, 17—17 and 18—18 of Fig. 13;

Fig. 19 is a fragmentary plan section taken along the line 19—19 of Fig. 13; and

Fig. 20 is a vertical section taken along the line 20—20 of Fig. 14.

For purposes of disclosure the invention is herein illustrated as embodied in a hammer type stapling device or tool 33 which comprises a pair of elongated channel members 32 and 34 made from sheet metal stampings and arranged with the lower channel 32 disposed in a partially housed relation within the upper channel 34, and these channels 32 and 34 are pivoted together at their right hand or rear ends by pivot screws 35 so that in a staple driving operation the forward or left hand end of the upper channel 34 may move downwardly with respect to the channel 32 from the position of Fig. 2 to the position of Fig. 3. The right hand or rear portion of the upper channel 34 constitutes the handle portion of the device or tool, and while grasp-

ing this handle the tool is swung downwardly through a hammer-like driving stroke so that the lower left hand face of the lower channel 32 is brought into contact with the surface of the work, such as a pair of superposed work pieces W-1 and W-2, which are to be connected together by a staple S. The staples S as herein shown are of the type wherein the upper cross bar has two legs of equal length extended downwardly therefrom, but it will be understood that conventional staples having legs of unequal length may be employed where this is desirable.

The lower channel member 32 is utilized under the present invention to carry the staple holding and feeding means F and the staple driving ram mechanism R, such ram mechanism being disposed on channel 32 adjacent to the left hand or forward end as shown in Figs. 1 to 3 of the drawings. The other or upper channel member 34 serves primarily as a housing member and as a handle, since the right hand or rear end of this upper channel 34 is grasped by the user when the tool is to be utilized to drive a staple into the work.

The upper channel 34 is formed so as to be of substantially uniform cross section throughout most of its length, but at its forward or left hand end as shown in Figs. 1 to 3 of the drawings, the channel 34 has an upward extension 34E whereby operative clearance is provided within the channel for elements of the ram mechanism R (Fig. 3), as will hereinafter be described. The upper channel 34 has a top wall 34T, a forward end wall 34F and a rear end wall 34R, and at the opposite edges of the top wall 34T, side walls 34S are extended downwardly and are connected to the end walls 34F and 34R. Near the rear wall 34R, a bottom wall 34B is provided for a limited distance between the lower edges of the side walls 34S, and in the plane of the bottom wall 34B, each of the side walls 34S has an inwardly extended guide flange 34G which, as will be evident in Fig. 4 of the drawings, extends in a forward or left hand direction throughout a substantial portion of the length of the channel member 34. However, at a point spaced a short distance from the left hand or forward end of the member 34, the flanges 34G are terminated as at 34C so as to afford a clearance opening in this area that is of the full width of the channel and this clearance opening, and the flanges 34G, are important, as will hereinafter be described, in permitting ready assembly of the parts as well as in attaining a guiding action between the parts after such assembly.

The lower channel 32 is formed so as to face upwardly and this channel has, in the left hand or forward portion thereof, a true channel form, while at the right hand end portion, the web or cross member of the channel is cut away to afford clearance to facilitate loading of staples S into the staple holding and feeding mechanism, as will hereinafter be described. In this portion it will also be noted that the vertical width of the side walls 32S has been reduced so that the handle portion of the channel 34 may be grasped without contact with the side walls 32S. Thus, the lower channel 32, in the forward or left hand portion thereof, has a bottom wall 32B and upstanding side walls 32S, and these side walls are so spaced that they have what may be termed a loose sliding fit against and between the two guide flanges 34G of the upper channel 34. The bottom channel wall 32B ter-

minates at its rear end at 32T substantially midway between the ends of the member 32, and from the edge 32T and substantially to the forward or left hand end of the channel 32, a staple supporting and guiding means is provided within the channel and on top of the bottom wall 32B. This guiding means may be attained in a simple manner through the mounting of a channel member 38 within the channel 32, and with the cross wall or web of the channel 38 secured as by means of screws 39 disposed within the channel 38 and extended through the bottom wall or web thereof into the bottom wall 32B of the channel 32. The side walls of the channel 38 are spaced from the side walls 32S of the channel 32 so that the legs of the staples S may ride between the channel 38 and the walls 32S, and when the staples S are in this position, the cross members of the staples extend across the open top of the channel 38 and ride upon the upper edges of these side walls, as shown in Fig. 9 of the drawings. When the staples S are in this position, they are held downwardly with respect to the channel 38 by guide plates 40 that are secured as by welding to the inner faces of the side walls 32S.

The staples S that are thus supported and guided on the channel 38 are normally urged in a forward or left hand direction, Fig. 2, by a staple-advancing follower mechanism that includes a channel shaped follower 41 that rides on the channel 38 and within the space traversed by the staples S. The follower 41 has the web portion thereof arranged to ride on the upper edges of the side walls of the channel 38, and flanges 41F on the follower 41 ride in the spaces between the side walls 32S and the channel 38. On the web of the follower 41 a bracket 42 is secured, and an elongated actuating rod 43 is slidably extended through the bracket 42 longitudinally of the channel 32. This rod 43 extends rearwardly or to the right through an upwardly faced spacing channel 45 that is disposed between and secured as by welding to the side walls 32S, and this spacing channel 45 extends to the right hand or rear end of the side walls 32S and has an end wall 45E formed thereon. An expansive coil spring 46 surrounds the rod 43 between the end wall 45E and the bracket 42 so that this spring serves normally to urge the follower 41 in a left hand or staple advancing direction. At its forward or left hand end the rod 43 has a head 43H formed thereon so that by withdrawing the rod 43 in a rearward or right hand direction the follower 41 may be withdrawn from its position within the staple guideway. This operation is facilitated through the provision of a knurled head 48 that is screw-threaded onto the rear or right hand end of the rod 43. To enable this to be done, a clearance opening 34C is provided in the rear wall 34R of the upper channel. The head 48 has a flange 48F formed thereon so as to be disposed within the channel 34, and a spring latch 49 secured to the web of the channel 45 is arranged to engage this flange to latch the rod in its forward or left hand position as shown in Fig. 2.

When the tool is to be loaded with staples, the handle 48 of the rod 43 is grasped and the follower 41 is withdrawn, and when the follower has been completely moved out of the staple guiding channel or passage the rod 43 is tilted so as to move the follower 41 upwardly into a clearance space 50 formed between the plates 75 40 and the channel 45, such clearance space being

shown in Fig. 2, and the location of the follower 41 in such clearance space being illustrated in Fig. 14 of the drawings. With respect to this positioning of the follower 41, it should be observed that the lower face of the web of the channel 45 is disposed substantially in the plane of the lower edges of the guide plates 40, and the lower edges of the flanges 41F of the follower are disposed only a slight distance above this plane when the follower has been moved into the clearance space 50. Thus, when the tool is turned over so that the open bottom edge thereof is exposed, the staples, which of course are furnished in joined groups or units in conventional fashion, may be readily loaded into the tool merely by placing them in an inverted position on top of the web of the spacing channel 45. These staples may then be moved forwardly or to the left into the staple guide passage, after which the follower may be moved out of the clearance space 50 and into alignment with the staple guiding passage, and upon release of the rod 43 the spring 46 will become effective to cause the follower 41 to urge the staples S in a forward direction through the guide passage and toward the staple driving ram mechanism R. The spacer channel member 45 is rigidly secured to and is located between the rearward extensions of the lower channel member 32 and the web portion of the spacer member 45 is located above the lower edges of the rearward extensions of the lower member 32, as clearly illustrated in Figs. 2 and 16 of the drawings, and when the tool is inverted for loading purposes the web of the spacer member 45 is adapted to support a group of staples in position for feeding onto the staple supporting member 38 which is mounted upon the bottom of the lower channel member 32 at the front portion thereof.

The desired pivotal connection between the channels 32 and 34 and at the right hand or rear end thereof is afforded by means that are best shown in Figs. 1, 17 and 19. Thus, it will be evident that the side walls 34S are recessed at 55 to receive the heads of the mounting pivot studs or screws 35 which have shouldered portions extending through pivot openings provided at the bottoms of the recesses 55, and the threaded portions of the pivot screws or studs 35 are threaded into the side walls 32S and the side flanges of the spacing channel 45. It will be observed that at the portions surrounding the pivots 35, the side walls 32S are somewhat thickened as at 32T, Figs. 4 and 19, and therefore when the device is to be assembled, this thickened portion is inserted into the clearance space forwardly of the ends 34C of the flanges 34G, and the lower channel 32 is then moved longitudinally into the channel 34 until the thickened portions 32T are disposed in the proper position for insertion of the pivot screws 35.

The present invention affords an extremely simple way in which to afford accurate cooperation of the elements of the ram mechanism R, and in accomplishing this, the ram mechanism R is provided with a relatively simple, but accurately formed, casting or machined element in the form of a vertical bar 60 which acts as a guiding element. The bar 60 is disposed between the forward edges of the side walls 32S, and this bar 60 is secured in position by a plurality of rivets 62 that extend transversely through the side walls 32S and the bar 60. These rivets 62 also serve to secure a pair of angle members 64 on opposite outer sides of the two side walls 32S, and these guide angles have flanges 64F that ride with a

relatively loose sliding action against the inner faces of the side walls 34S to serve as a lateral guiding means for the front portion of the channel 34 with respect to the front portion of the channel 32. In its rear face, the vertical guide bar 60 has a semi-circular guide groove 60G formed therein, and a staple-driving plunger P is arranged to ride vertically along this semi-circular guideway 60G. The plunger P has the lower portion thereof cut away as at 68, and a flat driving plate 70 is secured as by welding against this cut away portion of the plunger P so that this driving plate 70 will ride against the rearwardly flat faces 60R of the block or bar 60 on the opposite side of the guide groove 60G. The driving plate 70 is thus disposed in a vertical guideway defined at the front by the surfaces 60R, at the rear by the forward ends of the plates 40 and the forward end surfaces of the channel 38, and at its side edges by the side walls 32S, as will be evident in Figs. 11 and 12. The plunger P has a head 72 formed at its upper end, and below this head an expansive coil spring 74 surrounds the cylindrical portion of the plunger P. The lower end of this spring 74 acts on the upper end of the guide bar 60 and on a retaining and guiding web 78 that is formed by extensions from the two guiding plates 40. The web 78 cooperates with the guide channel 60G to afford a full circular bearing for the cylindrical upper portion of the plunger P.

It will be observed (Fig. 6) that an inwardly struck lug 24L is afforded in the front wall 34F of the upper channel 34, and a hook shaped member 60H on the bar 60 engages the lug 34L to limit the upward movement of the forward end of the channel 34 that is caused by the spring 74. In the assembly of the tool, the channel 32 is moved rearwardly in the channel 34 in an amount sufficient to let the hook 60H move upwardly past the lug 34L, and is then returned to the left or frontwardly to align the pivot elements of the structures. When the plunger P is in the upper or fully retracted position that is determined by the engagement of the lug 34L with the hook 60H, the lower end of the driving plate 70 is disposed just above the plane of the upper surfaces of the staples in the staple guiding channel, as will be evident in Figs. 2 and 6. Thus, the staple advancing means will urge the leading staple S into a position immediately beneath the staple driving plate 70, and in this position the staple will be disposed over the lower discharge opening that is afforded between the forward end edge of the bottom wall 32B and the rear face 60R of the guide bar 60. The lower portion of the plunger P is preferably cut away as at 70C, so that when the plunger is fully projected, only the rectangular lower end of the plate 70 will be exposed.

It will be observed that the rounded upper surface of the head 72 of the plunger P is engaged with a relatively thick and hardened bearing plate 80 that is fixed as by welding on the inner surface of the top of the extension 34E of the upper channel, and in the use of the present tool, the action of the elements is such that when the lower surface of the forward end of the channel 32 is brought into contact with the work W at the end of a hammer-like stroke, the plunger P will be driven downwardly so as to impart the desired driving force to the leading staple S as will be evident from a comparison of Figs. 2 and 3 of the drawings. In this connection it will be observed that the forward lower corner of the

bottom wall 32B and of the guiding bar 60, as well as the side walls 32S and the angles 64, are somewhat beveled and rounded as at 82, Fig. 1, thereby to afford greater latitude in the angle at which the tool may be brought into cooperation with the work. Similarly, the lower forward portions of the walls 34F and 34S are cut away as at 82A, for the same reasons.

It has been found in practice that the present tool operates without any objectionable tendency to mark or scar work at the point where the tool strikes the work, and while the work must, of course, absorb some of the inertia of the parts, it is the applicant's present theory that the avoidance of denting or marking of the work is due in a large measure to the novel cooperation of the elements of the ram mechanism whereby all binding is avoided.

From the foregoing it will be apparent that the present invention greatly simplifies the manufacture of hammer type stapling devices, and that it enables these stapling devices to be constructed in such a way as to involve but very few parts that may be manufactured and assembled in a simple and economical manner. It will also be evident that the present invention materially simplifies the loading of staples into the stapling tool, and that the parts of the staple holding and loading mechanism are of a simple character.

It will also be apparent that the present invention enables hammer type stapling devices to be used in many situations where prior devices of this type could not be used, since the present device avoids an objectionable marking or denting of the work surface adjacent to the point where the staple is driven.

Thus, while I have illustrated and described the preferred embodiment of my invention, it is to be understood that this is capable of variation and modification and I therefore do not wish to be limited to the precise details set forth, but desire to avail myself of such changes and alterations as fall within the purview of the following claims.

I claim:

1. In a stapling tool, a channel member having a bottom wall and upstanding side walls provided with rearward extensions of substantial length extending beyond the bottom wall, staple-guiding means mounted on said bottom wall, and upwardly facing spacer channel member rigidly secured between said rearward extensions in parallel relation to the staple guiding means and in position to locate a group of staples in alignment with said staple guiding means in the course of a loading operation, an end abutment wall in fixed relation to said rearward extensions and located at the rear end of said spacer channel member, a rod extended slidably through said end abutment wall and through said spacer channel member and over said staple guiding means, a follower slidably mounted on said rod, a spring means on said rod between said abutment wall

and said follower for urging the follower in a forward direction, said rod being movable rearwardly for withdrawing said follower from said staple guiding means, said spacer channel member being spaced from the staple guiding means to afford clearance space in which said follower may be moved upon such withdrawal.

2. In a stapling tool, a channel member having a bottom wall and upstanding side walls provided with rearward extensions of substantial length extending beyond the bottom wall, staple guiding means mounted on said bottom wall, an upwardly facing spacer channel member rigidly secured between said rearward extensions in parallel relation to the staple guiding means and in position to locate a group of staples in alignment with said staple guiding means in the course of a loading operation, an end abutment wall in fixed relation to said rearward extensions and located at the rear end of said spacer channel member, a rod extended slidably through said end abutment wall and through said spacer channel member and over said staple guiding means, a follower slidably mounted on said rod, a spring means on said rod between said abutment wall and said follower for urging the follower in a forward direction, said rod being movable rearwardly for withdrawing said follower from said staple guiding means, said spacer channel member being spaced from the staple guiding means to afford clearance space in which said follower may be moved upon such withdrawal, and means for detachably locking the rod in its forward position.

3. In a stapling tool, a channel member having a bottom wall and upstanding side walls provided with rearward extensions of substantial length extending beyond the bottom wall, staple guiding means mounted on said bottom wall, an upwardly facing spacer channel member rigidly secured between said rearward extensions in parallel relation to the staple guiding means and in position to locate a group of staples in alignment with said staple guiding means in the course of a loading operation, an end abutment wall in fixed relation to said rearward extensions and located at the rear end of said spacer channel member, a rod extended slidably through said end abutment wall and through said spacer channel member and over said staple guiding means, a follower slidably mounted on said rod, a spring means on said rod between said abutment wall and said follower for urging the follower in a forward direction, an exteriorly arranged head on said rod for withdrawing said follower from said staple guiding means, said spacer channel member being spaced from said staple guiding means to afford clearance space into which said follower may be moved upon such withdrawal, a latch secured to said spacer member and projecting beyond said abutment wall, and means carried by the rod for engaging the latch for locking the rod in its forward position.

131 war a position.
